SHIRT CONSTRUCTION

Walter I. Jones, Somerville, Mass., assignor to
 United-Carr Fastener Corporation, Cambridge,
 Mass., a corporation of Massachusetts

Application November 19, 1949, Serial No. 128,423

7 Claims. (Cl. 2—128)

1

This invention relates generally to articles of apparel such as shirts and the like, and has particular reference to such an article having snap fastener means disposed thereon to enable edge portions forming a front opening to be snapped together to close the opening.

The provision of snap fasteners on certain articles of clothing in place of buttons has been found desirable for a number of reasons. Such fasteners are more durable in that they are not subject to breakage, and they may be more securely attached to the cloth so that they will not be accidentally torn from the garment during use or during laundering operations. The use of such fasteners also materially reduces the cost of the garment, since they may be more rapidly and cheaply attached than buttons, which require relatively expensive operations for forming the button hole and sewing on the button.

However, it has not been possible to obtain these advantages with certain articles of clothing such as shirts and the like, since with conventional methods of shirt construction and snap fastener attachment, the attaching portion of one of the snap fastener halves is exposed on the outer surface of the garment, consequently it has been necessary to assemble a decorative button on the exposed portion of the fastener to conceal the attaching portion. The provision of such a button greatly increases the cost of the assembly, since not only are the buttons themselves expensive, but assembly operations necessary to attach the button to the fastener are relatively more difficult. The use of such decorative buttons on the fasteners also destroys the other advantages obtained by the use of snap fasteners instead of buttons and buttonholes, since such decorative buttons are frequently destroyed or damaged in laundering operations and interfere with fine laundering.

An object of the invention is to provide an article of apparel such as a shirt or the like having snap fasteners disposed thereon, in which the article is so constructed that no portion of the fastener is exposed when the garment is in use.

A further object of the invention is to provide an article of apparel such as a shirt or the like in which snap fasteners provided to close a front opening are so disposed in the portions of the material adjacent the opening as to completely conceal the fastener when the article is in use.

A still further object of the invention is to provide a garment such as a shirt or the like having a tape carrying a series of snap fastener halves

2

disposed on the inside of an overlapping edge portion of a front opening, in which the tape is so constructed as to provide a layer of cloth between the snap fastener half and the material of the edge portion to which it is attached.

Other objects of the invention will, in part, be obvious, and will, in part, appear hereinafter. For a fuller understanding of the nature and objects of the invention, reference should be had to the following detailed description, taken in conjunction with the accompanying drawings, in which:

Fig. 1 is a front view of a shirt member embodying the features of the invention;

Fig. 2 is an enlarged view in elevation, partly broken away, of the edge portions of the front opening of the shirt of Fig. 1;

Fig. 3 is an enlarged view in elevation, partly broken away of a modified form of shirt construction within the scope of the invention in which a tape carrying snap fastener halves is attached to the inside of an overlapping edge portion of the front opening;

Fig. 4 is a view similar to Fig. 3 of a modified form of the device in which the tape carrying the snap fastener halves is constructed in such a manner as to provide a cushioning layer between the attaching member of the snap fastener half and the panel to which the tape is applied;

Fig. 5 is a view similar to Fig. 3, of a modified form of the device of Fig. 3, in which the tape carrying the snap fastener halves has certain modifications within the scope of the invention;

Fig. 6 is a view in section taken on the line 6—6 of Fig. 2;

Fig. 7 is a view in section taken on the line 7—7 of Fig. 3;

Fig. 8 is a view in section taken on line 8—8 of Fig. 4; and

Fig. 9 is a view in section taken on line 8—8 of Fig. 5.

Referring to the drawing, there is illustrated a shirt 10, which comprises a fabric body portion 12, having a front opening 14 formed by an overlapping edge 16 and an overlapped edge 18. In all of the illustrated embodiments of the invention the overlapping edge 16 is provided with a longitudinal front panel 20, having a plurality of layers 22 of material, formed by folding and refolding upon itself a body extension member 24 which is attached to the body member by stitching 26. A panel center member 28, which may be formed of relatively stiff fabric, may also be disposed in the layers of the panel to assist in imparting stiffness thereto. The folds of the

panel and the center member are held together, in the embodiment of Figs. 2 and 6, by stitchings 30 spaced inwardly from each edge of the panel.

Referring to the embodiment of Figs. 2 and 6, to provide means for retaining the edge portions in the closed position, a series of snap fastener halves 32 and 34 are provided on the edge portions 16 and 18 respectively. The snap fastener halves 34 are attached to the edge portion 18 in the usual manner, with an engaging portion 36 disposed on the outer surface thereof. The snap fastener halves 32, which comprise an engaging portion 38 and an attaching portion 40 are assembled on the overlapping edge by attachment to an inner layer of the panel, preferably to the innermost layer 42, with the engaging portion disposed on the innermost surface thereof for engagement with the corresponding snap fastener half on the overlapped edge. The attaching portion 40 is disposed on the opposite side of the layer 42, and is wholly concealed within the folds of the panel 20, which eliminates any need of decorative buttons or other devices on the front of the panel 20. By attaching the snap fastener half 32 to the innermost layer 42 of the panel, a maximum number of thicknesses of material are provided between the attaching portion 40 and the outside surface of the panel, which protects the outside surface from receiving an impression from the attaching portion during laundering and ironing of the garment especially when the shirt is starched.

Referring now to the embodiment of Figs. 3 and 7, the panel member 20 is provided with a tape 44 on the rear or inside surface, which may be conveniently attached to the panel by stitching 46 which also holds the layers of the panel together. The tape 44 carries a series of snap fastener halves 48, which are attached thereto in the usual manner, with an engaging portion 50 disposed on the rear surface thereof for engagement with corresponding snap fastener halves disposed on the overlapped edge, and an attaching portion 52 disposed on the opposite side of the tape. With this construction, a quantity of tape with snap fastener halves attached may be prepared, and lengths of the tape may be cut for application to garments of various sizes. This construction also provides an extra layer of material between the attaching portion 52 of the outer surface of the panel.

Referring now to the embodiment of Figs. 4 and 8, the panel member 20 is provided with a tape 56 attached to the rear surface thereof, which has two layers 58 and 59 of material joined by a fold 60 along one edge. The tape 56 carries a series of snap fastener halves 62 on the innermost layer with an engaging portion 64 disposed in the rear surface for engagement with corresponding snap fastener halves on the overlapped edge, and an attaching portion 66 disposed between the two layers. As hereinbefore described, the tape may conveniently be prepared in quantity, and attached to the panel during manufacture of the shirt by stitching 68 which also hold the panel together.

Referring now to the embodiment of Figs. 5 and 9, the panel 20 is provided with a tape 70 attached to the rear surface thereof, which has an innermost layer 72 carrying snap fastener halves 74, and a pair of layers 76 and 78 which have been folded one over the other on the front side of the layer 72, and are attached thereto along folds 80 and 82. The engaging portion 84 of the snap fastener half is disposed on the rear surface of the layer 72 for engagement with

corresponding snap fastener halves on the overlapped member, and the attaching member 86 is disposed between the layer 72 and the adjacent layer 76. This method of construction provides a double layer of material between the attaching member 86 and the panel 20. The tape 70 may conveniently be attached to the panel 20 by stitchings 88, which are spaced inwardly from the edge of the panel to pass through all layers of the tape. As in the case of the embodiment of Figs. 4 and 7, a quantity of the tape may be prepared with snap fastener halves attached and applied to the shirt during manufacture of the panel.

In all embodiments of the invention, the attaching member of the snap fastener half disposed on the overlapping edge portion is wholly concealed behind the panel thereby eliminating the use of expensive decorative buttons or other devices on the outside of the panel. Also, in all cases the attaching member is separated from the outermost or front layer of the panel by a plurality of layers of material, to prevent any impression of the attaching member from showing on the front panel. The layers also provide a cushioning action to prevent damage to the fastener which might otherwise result when the garment is subjected to treatment in devices such as are in use in commercial laundries, which utilize high pressures and temperatures to effect an ironing operation.

Although all illustrated embodiments of the device are shown to have a front panel formed from a body extension member, it will be understood that this is exemplary only, since the principles of the invention are also applicable to that type of garment in which the overlapping edge is an integral part of the body portion.

Since certain other obvious modifications may be made in the device without departing from the scope of the invention, it is intended that all matter contained herein be interpreted in an illustrative and not in a limiting sense.

I claim:

1. A launderable article of apparel such as a shirt or the like, having a front opening formed by an overlapped edge portion and an overlapping edge portion, said overlapping edge portion having a plurality of plies of material extending longitudinally thereof at least one of the intermediate plies being of material relatively stiffer than that of the other plies to provide stiffening reinforcement for said overlapping edge portion; a series of snap fastener halves assembled on said overlapping edge portion comprising an engaging portion disposed on the inner surface of said plies, and an attaching portion disposed between the plies of material and wholly concealed therein by at least two plies of material to act as a cushion for the purpose described, said overlapped edge portion having a series of snap fastener halves disposed thereon to enable the edges to be snapped together.

2. A launderable shirt having a front opening formed by an overlapped edge portion and an overlapping edge portion, said overlapping edge portion having an outer longitudinal panel formed of a plurality of plies of material at least one of the intermediate plies being of material relatively stiffer than that of the other plies to provide stiffening reinforcement for said overlapping edge portion, and having a series of snap fastener halves assembled in concealed relation to said panel, said snap fastener halves comprising an engaging portion disposed on the inner surface of the overlapping edge portion and an

attaching portion disposed beneath at least two plies of the material in the panel, one of which plies being an intermediate ply of stiffer material, said overlapped edge portion having a series of snap fastener halves disposed thereon to enable the edges to be snapped together.

3. A launderable shirt construction having a front opening formed by edge portions adapted to be fastened together in superimposed relation, one of said edge portions having a panel formed by folding and refolding upon itself to provide a plurality of plies of material, said panel having an additional intermediate ply of material relatively stiffer than that of said panel, and a tape disposed on the inner surface of said panel, said tape and said plurality of plies of material being stitched together by a pair of longitudinal stitchings spaced inwardly from each edge of the panel, said tape having a series of snap fastener halves disposed thereon with an engaging portion on the inner surface thereof, and an attaching portion disposed between the tape and the panel and wholly concealed therebetween, the other of said edges having a corresponding series of snap fastener halves disposed thereon to enable the edges to be snapped together.

4. A launderable shirt construction having a front opening formed by edge portions adapted to be fastened together in superimposed relation, one of said edge portions having a panel formed by folding and refolding upon itself to provide a plurality of plies of material, said panel having an additional intermediate ply of material relatively stiffer than that of said panel; a tape disposed on the inner surface of said panel, said tape being folded longitudinally to form at least two layers of material, the layers of said tape and said plies of the panel being held together by a pair of longitudinal stitchings spaced inwardly from each edge of the panel; a series of snap fastener halves secured to the innermost layer of the tape with an engaging portion on the inner surface thereof and an attaching portion disposed between the layers of the tape and wholly concealed therebetween, the other of said edges having a corresponding series of snap fastener halves disposed thereon to enable the edges to be snapped together.

5. A launderable shirt construction having a front opening formed by edge portions adapted to be superimposed and fastened together, one of said edge portions having a tape disposed longitudinally on the inner surface thereof and a stiffening element overlying said tape, said tape being folded longitudinally to form a plurality of layers of material, and having a series of snap fastener halves disposed thereon on the innermost layer, said snap fastener halves comprising

an engaging portion disposed on the inner surface of the innermost layer, and an attaching portion on the opposite side of said innermost layer, whereby said attaching portion is wholly concealed within the folds of the tape, the other of said edges having a series of corresponding snap fastener halves disposed thereon to enable the edges to be snapped together.

6. A launderable shirt having a front opening formed by an overlapped edge portion and an overlapping edge portion, said overlapping edge portion having a plurality of plies of material extending longitudinally thereof, an intermediate one of said plies being of material relatively stiffer than the material of the others; a tape disposed longitudinally on the inner surface thereof, said tape being folded longitudinally to form a plurality of layers, and a series of snap fastener halves disposed on the innermost layer of the tape having an engaging portion disposed on the innermost surface thereof and an attaching portion disposed on the opposite side, said attaching portion being wholly concealed within the folds of the tape; the other of said edges having a series of corresponding snap fastener halves disposed thereon to enable the edge portions to be snapped together.

7. A launderable article of apparel such as a shirt having a front opening formed by an overlapped edge portion and an overlapping edge portion, a series of snap fastener parts assembled on said overlapping edge portion each comprising an engaging portion disposed on the inner surface thereof and an attaching portion disposed between the inner and outer surfaces thereof, said overlapping edge portion being of multiple ply construction having an inner fastener carrying ply, an outer finish ply and an intermediate ply constituting a cushioning member, said cushioning member being of relatively greater thickness and stiffness than said outer finish ply so as to prevent impression of said fastener parts in said outer finish ply upon laundering and ironing said article of apparel, said overlapped edge portion having a series of corresponding snap fastener parts disposed thereon for snap fastener engagement with said first mentioned snap fastener parts to enable the edge portions to be snapped together.
